CONDUIT SUPPORT

Archibald T. Flower, Wyndmoor, Pa., and John A. Ten Brook, Landis Township, Cumberland County, N. J.

Application September 28, 1945, Serial No. 619,218

9 Claims. (Cl. 248—68)

1

This invention relates to conduit supports and more particularly to a support for laying electric conduits in a trench.

It is an object of the invention to provide an assemblage of supporting blocks for supporting a plurality of conduits in spaced parallel relation with means for anchoring the assemblage in its adjusted position in a trench.

A further object of the invention resides in providing an assemblage of supporting blocks having anchoring means adjustably connected therewith to permit adjustment in a vertical and sidewise direction to align and grade the conduits supported by the blocks.

Another object of the invention resides in providing a support of the above-mentioned character which is simple and durable in construction, reliable and efficient in use and inexpensive to manufacture.

Other objects and advantages of the invention will be apparent during the course of the following description.

In the accompanying drawing forming a part of this specification and in which like numerals are employed to designate like parts throughout the same,

Fig. 1 is a front elevational view of the support positioned in a trench,

Fig. 2 is a section taken on the line 2—2 of Fig. 1,

Fig. 3 is a vertical sectional view of the support after the support is embedded in concrete, and,

Fig. 4 is a section taken on line 4—4 of Fig. 1.

In the drawing wherein for the purpose of illustration a preferred embodiment of the invention is shown the support is generally designated by the numeral 5 and consists of an upper supporting block 6, a lower supporting block 7 and intermediate spacing block 8. The blocks forming the support are rectangular shape and made of concrete with reinforcing rods 9 embedded in the center thereof, as shown in Fig. 3. When assembled the blocks are disposed in vertical spaced relation and have opposed recesses 10 formed in their confronting faces to receive the fibre ducts 11 which carry the electric conduits.

A depending plate 12 is suspended from the center of the lower supporting block 7. The upper end of the plate is angularly bent, as at 13, to engage the side face of the block 7 to which it is attached by a bolt 14 passing transversely through the block. The blocks 6, 7 and 8 are held together in clamping engagement with the fibre ducts 11 by a tie wire 15 which passes through an opening 16 in the plate 12 and ex-

10 tends up both sides of the blocks with the free ends twisted together, as at 17, over the top of the upper supporting block 6.

The anchoring means for securing the support in the trench 18 consists of a pair of arms 19 and 20 having their inner ends disposed in overlapping relation and their outer ends twisted, as at 21, to form prongs 22 adapted to penetrate the side walls of the trench. The overlapping ends of the arms 19 and 20 are adapted to receive the depending plate 12 of the support therebetween and on each side of the plate the arms are secured together by bolts 23 and 24 which upon tightening firmly clamp the arms and plate together. Upon removal of either the bolt 23 or 24, the remaining bolt serves as a pivot to permit the arms to be folded preliminary to driving the arms into engagement with the walls of the trench.

20 When installing the support in a trench the anchoring means is first positioned in the bottom of the trench by folding the arms 19 and 20 which allows the arms to be lowered into the trench. With the prongs at the ends of the arms in engagement with the trench walls a force is applied to the arms above the pivot of the arms to spread the arms laterally and force the prongs to penetrate the walls until the arms are in a horizontal plane. After adjustment of the anchor arms the lower supporting block carrying the depending plate 12 is lowered in the trench with the plate inserted between the overlapped ends of the anchor arms. The supporting block 7 is adjusted vertically and sidewise to provide for proper alignment and grading of the conduits to be supported thereby and then the bolts 23 and 24 are tightened to firmly clamp the plate 12 between the anchor arms thus securing the block in its adjusted position. The conduits are then laid between the supporting blocks and secured together by the tie wire 15. After laying the conduits in the trench, the conduits including the support are completely encased in concrete 25 which is poured into the trench.

45 It is to be understood that the form of our invention herein shown and described is to be taken as a preferred example of the same and that changes in the shape, size and arrangement of the parts may be made within the scope of the subjoined claims.

50 Having thus described our invention, we claim:

1. A conduit support for laying conduits in a trench comprising opposed supporting blocks having recesses in their confronting faces to receive the conduits therein, means for securing said blocks in clamping engagement with said con-

duits, and anchoring means fixedly attached to the center of the lowermost block composed of folding arms adapted to be spread into holding engagement with the walls of the trench.

2. A conduit support for laying conduits in a trench comprising opposed blocks having recesses in their confronting faces to receive the conduits therein, means securing said blocks in clamping engagement with the conduits, a plate depending from the center of the lowermost block and fixedly attached thereto, and anchoring means adjustable longitudinally of said plate adapted to engage the walls of the trench.

3. A conduit support for laying conduits in a trench comprising opposed blocks having recesses in their confronting faces to receive the conduits therein, means securing said blocks in clamping engagement with the conduits, a plate depending from the center of the lowermost block and fixedly attached thereto, a pair of foldable anchor arms having their inner ends disposed in overlapping relation with said plate adjustably disposed therebetween, a bolt pivotally connecting said arms together to permit spreading of said arms into engagement with the walls of the trench and a second bolt for securing said arms in spread position and in clamping engagement with said plate.

4. A conduit support comprising a series of supporting blocks arranged in a vertical tier with opposed transverse recesses in their confronting faces to receive the conduits, means securing said blocks together and in clamping engagement with the conduits, a plate fixedly attached to the lowermost block and depending from the center thereof, and foldable arms adjustably connected to said plate adapted to be extended into gripping engagement with the walls of a trench.

5. A conduit support for laying conduits in a trench comprising opposed supporting blocks having recesses in their confronting faces to receive the conduits therein, means securing said blocks in clamping engagement with said conduits, and

vertically folding arms adjustably attached to the lowermost block adapted when extended to engage the walls of the trench.

6. A conduit support as described in claim 5 including means for securing said arms in extended position.

7. A conduit support for laying conduits in a trench comprising opposed supporting blocks having recesses in their confronting faces to receive the conduits therein, means securing said blocks in clamping engagement with said conduits, a stem depending from the lowermost block and fixedly attached thereto, and vertically folding arms adjustably mounted on said stem adapted when extended to engage the walls of the trench.

8. A conduit support as described in claim 7 including means for securing said arms in adjusted and extended position.

9. A conduit support for laying conduits in a trench comprising opposed supporting blocks having recesses in their confronting faces to receive the conduits therein, an anchoring post depending from the center of the lowermost block and fixedly attached thereto, and a tie wire passing around said blocks and through an opening in said anchoring post.
